UNITED STATES PATENT OFFICE.

LAWRENCE W. COUPE, OF NEW BEDFORD, MASSACHUSETTS, ASSIGNOR TO DRAPER CORPORATION, OF HOPEDALE, MASSACHUSETTS, A CORPORATION OF MAINE.

SHED-FORMING MECHANISM FOR LOOMS.

1,335,876.

Specification of Letters Patent.

Patented Apr. 6, 1920.

Application filed February 8, 1919. Serial No. 275,844.

To all whom it may concern:

Be it known that I, LAWRENCE W. COUPE, a citizen of the United States, and resident of New Bedford, county of Bristol, State of Massachusetts, have invented an Improvement in Shed-Forming Mechanisms for Looms, of which the following description, in connection with the accompanying drawing, is a specification, like characters on the drawing representing like parts.

This invention relates to improvements in shed forming mechanisms for looms and the principal object thereof is to provide means for insuring a smooth reciprocation of the harness irrespective of the amplitude of reciprocation which determines the width of the shed opening.

Another object of the invention is to provide means whereby the amplitude of reciprocation of the harnesses may be adjusted to vary the shed opening without necessitating a change of the cams for operating the harnesses, which mechanism will keep the cam followers in touch with the cams thereby preventing sudden and jumping movements which are likely to cause breakage of the warp ends.

A further object of the invention is to provide means for maintaining the cam followers at all times in contact with the cams, for the purpose above specified, which may be readily applied to and operated upon the usual types of looms.

Other objects and features of the invention will more fully appear from the following description and the accompanying drawings and will be pointed out in the concluding claims.

In the drawings:

Figure 1 is a vertical sectional view through a loom frame showing sufficient parts of the loom to illustrate my invention as applied thereto,

Fig. 2 is a detail view showing my invention as applied to the lower harness bars of a loom and the levers for actuating the same, and,

Fig. 3 is a detail side elevation showing the lower bars of a pair of harnesses, the levers and cams for operating them and the connections between said levers and said harnesses embodying my invention.

The invention is disclosed as applied to a usual type of Northrop loom comprising side frames 1, having upwardly extending

arch bars 2 which carry the shaft 3 of the harness rolls 4. Flexible straps 5 and 6 connected to the harness rolls 4 support, from the top, the front and rear harnesses 7 and 8 respectively so that as the harness rolls 4 are oscillated the harnesses 7 and 8 will be alternately raised and lowered. The harnesses 7 and 8 are provided with the usual heddles 9 and 10 through which the two sheets of warp ends 11 and 12 are carried and alternately crossed in the usual manner to form a shed through which the shuttle is driven.

The warp ends 11 and 12 run from the usual warp beam, not shown, over the whip roll 13 across the usual lease rods 14, 15 thence through the heddles 9 and 10 and through the reed 16 upon the lay 17 which is carried by the swords 18, which are oscillated through the link 19 from a crank 20 on the crank shaft 21. The cloth 22 as it is woven, is carried over the take-up roll to the cloth roll in the usual manner. The mechanism for reciprocating the harnesses may be of the usual type employed in looms, my invention being such that it may be applied to the ordinary loom structures.

As illustrated in the accompanying drawing the harnesses are actuated through cams 23, 24 carried by a cam shaft 25 journaled in the loom sides and rotated in any convenient manner. The cams 23 and 24 engage respectively cam following rollers 26 and 27 carried by levers 28 and 29 which are fulcrumed upon a rod 30 supported by a bracket 31 which is carried by a girder 32 connecting the loom sides.

The levers 28 and 29 are provided at their ends with the usual series of notches 33, 34 which permit the adjustment of the means connecting said levers to the harnesses to permit a greater or less reciprocating movement of the harnesses. The connecting means as illustrated herein comprises stirrups 35, 36 engaging respectively the notches 33 and 34 in the levers 28, 29 and straps 37 and 38 passing through said stirrups and through stirrups 39 and 40 depending from the lower bars 41, 42 of the harnesses 7 and 8. The straps 38 and 39 may be provided with the usual buckles whereby they may be adjusted as desired.

The construction thus described may be and is that of a usual type of loom. It is desirable at times to vary the width of the

shed opening when cloths of different character are being woven but when in ordinary looms adjustment is effected to give shorter reciprocation to the harness considerable lost motion occurs between the cams and cam followers which results in a jump or jerk when the cams come into action. This jumping or jerking causes a sudden tension upon the warp threads which results in serious breakage of warp ends.

The present invention is designed to overcome this defect and to permit the adjustment of the harness actuating mechanism in such a manner that a small shed opening 15 may be made by the use of ordinary cams without the necessity of changing from large to small cams. This is accomplished by providing means for introducing lost motion in the mechanism for actuating the 20 harnesses so that the harnesses will have only a portion of their normal movements, and by providing means which will prevent sudden movements or jerks when the actuating means becomes effective, whereby the 25 harnesses will be given a smooth reciprocating movement irrespective of the extent of their reciprocation.

By thus providing means eliminating all 30 jumping or jerking movements of the harnesses the shed opening may be adjusted without changing the cams so that cloth may be woven from fine yarns with high slay such as that employed for aeroplane cloth. Thus without danger of warp breakage and 35 without the loss of time and expense required to change the cams, an ordinary loom, with this invention, may have its shed opening adjusted simply and quickly to meet a wide range of requirements.

40 Any suitable means may be provided for preventing lost motion in the actuating mechanism which reciprocates the harnesses within the spirit and scope of my invention. The preferred mechanism which is disclosed 45 herein and which may be readily applied to usual looms, without the necessity of modifying the structure of the loom, comprises one or preferably a pair of spiral springs 43, 44 connected at their lower ends to the stirrups 35, or 36 which engage the levers 28, 29 and at their upper ends to the stirrups 39, 40 which depend from the lower harness bars 41, 42.

As illustrated herein the lower ends of the 55 springs 43, 44 have their ends 45, 46 bent around the stirrup 35 or 36 and their upper ends 47, 48 connected to hooks 49, 50 which are hooked over the horizontal bars 51, 52 of the stirrups 39 and 40. The springs 43, 60 44 desirably are arranged in pairs which may be conveniently located at the sides of the respective straps 37, 38. The springs 43, 44 desirably are of such strength as to retain the cam following rollers 26, 27 in contact 65 with the cams 23 and 24 at all times.

When the positive connecting means, such as the straps, between the ends of the levers 28 and 29 and the harnesses are adjusted to narrow the shed opening it will be seen that unless means are provided to eliminate lost motion the cams 23 and 24 will only contact with the followers during a portion of the movement of the levers and during the remaining portion of the movement the levers will be free to remain out of contact with the cams. With this invention applied the springs or resilient connecting means between the levers and harnesses act, no matter what adjustment may be made of the positive connecting means, to hold the followers of the levers 28 and 29 always against the cams 23 and 24 so that no lost motion can take place and there is at all times a steady and easy movement of the harnesses.

By thus preventing lost motion ordinary 85 looms can be adjusted to form narrow sheds without the necessity of changing from the ordinary large cams to small cams. This enables a greater variety of work to be performed upon the same looms without re- 90 placement of parts or inconvenience, since to vary the width of shed opening it is merely necessary to adjust either the connections of the stirrups 35, 36 with the notches 33, 34 of the levers 28, 29 or the length of the 95 straps 37, 38 which connect said levers with the harnesses, or both.

Having thus described my invention, what I claim as new and desire to secure by Letters Patent is:

1. Shed forming mechanism for looms, comprising relatively movable harnesses, actuating means therefor, positive means for transmitting movement from said actuating means to said harnesses, having means of adjustment to introduce lost motion between said actuating means and said harnesses during a portion of the cycle of movement of said actuating means, whereby the amplitude of reciprocation of said harnesses may be varied and shed openings of different widths produced, and means for preventing sudden jerking movements of said harnesses when said actuating means effectively acts upon said positive transmitting means. 110

2. Shed forming mechanism for looms, comprising relatively movable harnesses, actuating means therefor, positive means for transmitting movement from said actuating means to said harnesses, having means of adjustment to introduce lost motion between said actuating means and said harnesses during a portion of the cycle of movement of said actuating means, whereby the amplitude of reciprocation of said harnesses may be varied and shed openings of different widths produced, and resilient means intermediate of said actuating means and said harnesses acting to prevent sudden jerking movements when the actuating means acts 120 125 130

effectively upon said positive transmitting means.

3. In a loom comprising a frame, a rotatable cam shaft and cams, a plurality of relatively movable harnesses, levers operable by said cams for reciprocating said harnesses and coöperating positive and resilient means connecting said levers to said harnesses, said positive means being operable 10 to impart to said harnesses reciprocating movements of predetermined amplitude and said resilient means operating to maintain said levers in contact with said cams.

4. In a loom comprising a frame, a rotatable cam shaft and cams, a plurality of relatively movable harnesses, levers operable by said cams for reciprocating said harnesses and coöperating positive and resilient means connecting said levers to said harnesses, said positive means being operable to 20 impart to said harnesses reciprocating movements of predetermined amplitude and said resilient means operating to maintain said levers in contact with said cams and means 25 for adjusting said positive connecting means whereby the width of the opening in the shed may be varied.

5. In a loom comprising a frame a rotatable cam shaft and cams, a pair of harnesses, supporting means including flexible members connected to the upper bars of said harnesses, means for alternately reciprocating said harnesses in opposite directions including levers engaging said cams, adjust-

able inextensible means connecting said levers to the lower bars of said harnesses and resilient means also connecting said levers to the lower bars of said harnesses operating to maintain said levers in contact with said cams.

6. In a loom comprising a frame, a rotatable cam shaft and cams, a pair of harnesses, supporting means including flexible members connecting the upper bars of said harnesses, means for alternately reciprocating 40 said harnesses in opposite directions including levers engaging said cams, straps positively connecting said levers to the lower bars of said harnesses and helical springs 45 also connecting said levers to said harnesses 50 operating to maintain said levers in engagement with said cams.

7. In a loom comprising a frame, a rotatable cam shaft and cams, a pair of harnesses, supporting means including flexible 55 members connected to the upper ends of said harnesses, means for alternately reciprocating said harnesses in opposite directions including levers engaging said cams, stirrups on said levers, adjustable straps connecting 60 said lever stirrups to stirrups depending from said harness and helical springs also connecting said lever stirrups to said harness stirrups.

In testimony whereof I have signed my 65 name to this specification.

LAWRENCE W. COUPE.
